UNITED STATES PATENT OFFICE.

MICHAEL F. BROGAN, OF LAWRENCE, MASSACHUSETTS.

SAFETY-RAZOR.

1,145,466.

Specification of Letters Patent. Patented July 6, 1915.

Application filed August 26, 1914. Serial No. 858,628.

To all whom it may concern:

Be it known that I, MICHAEL F. BROGAN, a citizen of the United States, residing at Lawrence, in the county of Essex and State 5 Massachusetts, have invented certain new and useful Improvements in Safety-Razors; and I do hereby declare the following to be a full, clear, and exact description of the invention, such as will enable others skilled in 10 the art to which it appertains to make and use the same.

The present invention relates to improvements in safety razors, and more particularly to razors of this type which are operated manually.

The object of the present invention is to provide an improved form of safety razor which is extremely compact and which presents a maximum effective cutting edge with 20 the blade clamped securely in operative position.

With this object in view the several features of the invention consist in certain novel features of construction, combinations and 25 arrangements of parts, the advantages of which will be obvious to those skilled in the art from the following description.

In the accompanying drawings illustrating the preferred form of the invention; 30 Figure 1 represents a front view of the razor with the handle attached ready for use; Fig. 2 is a side view of the construction shown in Fig. 1; Fig. 3 is a longitudinal section upon an enlarged scale of the construction 35 shown in Fig. 1; Fig. 4 is a cross section upon the line 4-4 of Fig. 3; Fig. 5 is a cross section upon the line 5-5 of Fig. 3; Fig. 6 is a view partly in section illustrating 40 the manner in which the handle is inserted in the holder when not in use; Fig. 7 is a view showing the blade clamping member; Fig. 8 is a view of the blade holder; and Fig. 9 is a view showing the curved 45 razor blade.

In the illustrated embodiment of the invention a razor blade 1 is clamped to a cylindrical holder 3 having an opening extending throughout its length. The blade is shaped to conform to the curvature of the holder 50 and is provided with cutting edges which overlie and extend parallel to the opposite edges of the opening in the holder, as shown clearly in Figs. 3 and 4. In order to guard the cutting edges of the blade, the holder is

provided upon each edge of the opening 55 with a series of guard fingers 4 which are curved in conformity with the curvature of the holder and extend beyond the cutting edges of the blade in the usual manner. The blade member 1 is formed of a thin, resilient 60 sheet of metal bent to the required shape and clamped to the holder by a clamping member 6 which is connected to the holder 3 at one end by the engagement of a slot 7 with an undercut lug 8, as shown clearly in 65 Figs. 3, 7 and 8. The opposite end of the clamping member 6 is provided with an annular ring 9 which loosely surrounds a stud 10 extending from the holder 3 and threaded to receive a handle portion 12 70 which serves to clamp the ring 9 to the face 13 of the holder, as shown clearly in Fig. 6. In order to prevent the displacement of the blade member 1 relative to the holder, either longitudinally or angularly, the blade mem- 75 ber is provided with a slot 15 which embraces the lug 8 formed upon the holder, and a small recess 16 arranged to receive a pin 17 projecting from the inner surface of the clamping member to secure the blade in 80 position at its opposite end. It will be ob- 85 vious to those skilled in the art that if the blade is always clamped in the same position in the holder, substantially only one cutting edge will be employed and in order to prolong the life of the blade it is made reversible, as shown clearly in Fig. 9, by providing a rectangular slot 15 and a recess 16 at each end of the blade in order that the position of the blade may be conven- 90 tiently reversed when desired. It will be noted that this construction is extremely compact in form and provides a maximum clamping area for the blade, insuring that the blade will be held rigidly in position and 95 effectually preventing any tendency of the blade to spring away from the holder and inflict a cut. With the present construction the rounded surface presented by the holder and clamping member enables the razor to 100 be successfully manipulated in hollows and depressions in the face and cut the hair much closer to the skin than is possible with a razor having a flat blade or guard. Furthermore, the thin metallic blade curved in 105 conformity with the curvature of the clamping member and holder enables the various parts to be formed upon an arc of relatively

short radius and at the same time causes the surface of the blade to adhere closely to the surface of the holder, thus more effectively protecting the cutting edge. A further advantage of the curved type of blade resides in the fact that it can only be resharpened by the employment of special apparatus and the user is compelled to either buy new blades when the old ones become dull, or re-sharpen them in the manner or with the apparatus designated by the manufacturer.

In order to hold the razor more securely when in operation the handle portion is made extensible by the provision of a tubular member 18 which is provided with a stud 20 threadedly received in the end of the handle member 12, as shown clearly in Fig. 3. When not in use the member 18 is inserted in the holder 3 and the stud 20 is threaded in the handle 12 from the opposite direction, as shown clearly in Fig. 6, the member 18 being provided with a reduced fluted portion 21 which is received within the holder 3.

While it is preferred to employ the specific construction and arrangement of parts shown and described, it will be understood that this construction and arrangement is not essential except so far as specified in the claims, and may be changed or modified without departing from the broader features of the invention.

The invention having been described, what is claimed is:

1. A safety razor, having in combination, a normally curved blade having parallel cutting edges extending in the direction of its length, a curved holder supporting the blade on the inside and having a lengthwise opening over which the cutting edges project, means for clamping the blade to the holder, and a handle extending in the direction of the length of the blade connected with the holder for conveniently manipulating the blade.

2. A safety razor, having in combination, a substantially cylindrical holder having a lengthwise opening, a normally curved blade surrounding the holder and having cutting edges overlying the opening, a clamping member surrounding the blade and secured to the holder, and a handle connected with the holder at one end and extending in the direction of the cutting edge of the blade.

3. A safety razor, having in combination, a curved holder having a lengthwise opening formed therein, guard fingers formed upon the opposite edges of the opening, a normally curved blade surrounding the holder and having a cutting edge contacting with the guard fingers, a clamping member engaging with the outside of the blade and secured to the holder, and a handle connected with the holder at one end.

4. A safety razor, having in combination, a substantially cylindrical holder, a stud connected to the holder, a razor blade, and a clamping member securing the razor blade to the holder having an annular ring surrounding the stud to position the clamping member relative to the holder.

5. A safety razor, having in combination, a substantially cylindrical holder, a normally curved blade secured upon the holder, connections between the holder and the end edges of the blade to position the blade upon the holder, a clamping member connected to the holder, and connections between the blade and clamping member.

6. A safety razor, having in combination, a clamping member, a holder, a normally curved blade interposed between the clamping member and holder and having recesses upon the opposite end edges, and a projection upon the holder arranged to engage with the recess in either end edge of the blade.

7. A safety razor, having in combination, a curved holder, a projection formed upon one end of the holder having an undercut surface, a blade surrounding the holder having a slot engaging with the undercut face of the projection, and a member for clamping the blade to the holder having a recess at one end engaging beneath the undercut face of the projection upon the holder and having a pin at its opposite end projecting into a co-operating recess formed in the holder.

8. A safety razor, having in combination, a curved holder having a stud projecting therefrom, a razor blade surrounding the holder, a clamping member, an annular ring formed upon the clamping member and surrounding the stud, and a handle threadedly connected to the stud and arranged to clamp the annular ring against one end of the holder.

9. A safety razor, having in combination, a substantially cylindrical holder, a razor blade secured thereto, a handle connected to the holder and having an internally threaded bore, and a second handle member having a threaded stud arranged to be received in either end of the bore.

10. A safety razor, having in combination, a normally curved blade having parallel cutting edges extending in the direction of its length, a curved holder supporting the blade on the inside and having a lengthwise opening over which the cutting edges project, connections between the blade and holder, and a handle connected with the holder at one end and extending in the direction of the length of the cutting edges for conveniently manipulating the blade.

11. A safety razor, having in combination, a substantially cylindrical holder, a normally curved razor blade surrounding

the holder and having parallel cutting edges, connections between the holder and blade, and a handle secured to one end of the holder.

5 12. A safety razor, having in combination, a two-edged blade, the body of which is substantially semi-cylindrical and the

edges of which project substantially parallel to each other, and a similarly shaped holder for holding said blade.
